UNITED STATES PATENT OFFICE.

HAROLD H. TURNER, OF CHICAGO, ILLINOIS.

MOTOR OR ENGINE.

1,275,503.

Specification of Letters Patent. Patented Aug. 13, 1918.

Application filed December 7, 1915. Serial No. 65,482.

To all whom it may concern:

Be it known that I, HAROLD H. TURNER, a citizen of the United States, residing at Chicago, in the county of Cook and State of Illinois, have invented certain new and useful Improvements in Motors or Engines, of which the following is a specification.

My invention relates to prime movers in which the combustion and explosion of an explosive within a confined chamber acts upon a body of mercury or other suitable liquid in said chamber to force such liquid through a passageway including a turbine casing and produces rotation of the turbine 10 therein, the liquid, after passing through the turbine passages being again conducted to the explosion chamber, and the cycle of operations repeated in the continued operation of the engine. In my pending application 15 filed September 22, 1915, Serial No. 52017, I have described one type of engine operating in this manner in which the operating body of liquid passes always through one and the same turbine chamber (although 20 two turbine wheels, each operated by an independent body of mercury, are preferably employed to produce a symmetrical operation of the engine), and in the present application will be described a type of engine in 25 which the body of liquid is driven from one combustion or explosion chamber, by the gases produced by the combustion of the fuel, through one turbine chamber into a similar and adjoining combustion chamber, 30 and by a succeeding explosion is returned through a second turbine chamber to the first-mentioned combustion chamber.

The object of my present invention is the production of a motor having the mode of 35 operation indicated, and which shall be simple and efficient and embody various features of novelty and utility which inhere in the construction hereinafter described and will be more particularly pointed out in the appended claims.

Of the drawings Figure 1 represents a vertical section taken on the line 1—1 of Fig. 2 centrally through one combustion chamber, in the plane of rotation of the turbine 40 wheel; Fig. 2 is a vertical section taken on the broken line 2—2 of Fig. 1, looking in the direction of the arrows; Fig. 3 is a top view of the intermediate casing member and partition inset therein, the turbine casing 45 being removed; Fig. 4 is a section on the

line 4—4 of Fig. 1, illustrating the construction of the partition plate and valves carried thereby; Fig. 5 is a side elevation of the engine, partly broken away and shown in section; Fig. 6 is a top plan view; Fig. 7 is 60 a horizontal section on the line 7—7 of Fig. 5; Fig. 8 is a vertical section centrally of the distributing valve, on the line 8—8 of Fig. 7; Fig. 9 is a side view of the motor, showing a modified form of valve embodying a carbureting piston, with connections for operating such piston; Fig. 9^a is a top plan view showing such connections; Fig. 10 is a vertical section of such valve, on the broken line 10—10 of Fig. 11; Fig. 11 is a 65 vertical section of the same, at right angles to the planes of Fig. 10 and on the line 11—11 of such figure; Fig. 12 is a front view of the connections for operating the carbureting piston; Fig. 13 is a side view 70 (the base plate at the side being removed) of an electric switch governing the explosions of vapor; Fig. 14 is a central cross section of the same; Fig. 15 is a view, similar to Fig. 2 but showing a modified form 75 of engine in which four turbine wheels are used; and Fig. 16 is a view similar to Fig. 8, but showing a modified arrangement of ports and passageways necessary to effect explosions in the four explosion chambers of 80 the four-turbine engine shown in Fig. 15.

The same letters of reference indicate the same parts in all the figures of the drawing.

The casing of my motor may be formed of any suitable or convenient number of 90 members formed to inclose the passageways for the body of mercury, and arranged to support the movable elements, and may be supported upon a suitable base or attached to any stationary or movable structure—not 95 illustrated,—according to the use to which it is put. In the embodiment shown the chambers 1, 1^a in which the explosions occur are formed in an intermediate casting A, and the turbine chambers 2, 2^a are formed 100 in an upper casting B secured firmly by bolts to the casting A. The lower parts of the outer wall of the casting A are made hollow, and a lower casting C bolted to such outer wall and constituting an extension of 105 it provides a water jacket space 3 surrounding the explosion chambers. The partition between these two chambers is made hollow or double, to permit circulation of water 110 between them, and two pipe connections 4

and 5 are provided through which circulation of the water may be effected by any suitable means, as a pump—not shown.

The explosion chambers 1 and 1^a are in free communication with the turbine chambers through two pipes 6 and 7 which respectively extend from adjacent the bottoms of such chambers to inlet passages 8 and 9 which are formed in the base portion of the turbine casting B, and are of such shape as to direct a jet of mercury forced therethrough against the blades of the wheels 10, 10^a. These pipes are firmly secured to such casting and to a partition plate 11 which is seated on a beveled seat formed around the inside of the wall of the casting A at its top. The bottom of the partition plates, as shown in Figs. 1 to 4, is inclined downwardly in two different planes, separated by a vertical central wall 12 continuous with a central wall or partition 13 which separates the two turbine chambers and is in alinement with the center of the hollow partition separating the explosion chambers 1 and 1^a. The inclined wall 14 above the explosion chamber 1, together with the side wall 15 and central partition 13 inclose an approximately triangular chamber which at the top communicates with the bottom of the turbine chamber 2, and at the bottom extends between downwardly inclined walls 16 and 17 to a chamber 18 lying above the explosion chamber 1^a. An upwardly opening check valve 18^a is arranged in the top wall of this chamber, the space thereabove opening into the explosion chamber 1^a through a triangular shaped outlet 19 in a partition 20 which extends transversely of the walls 15 and 12 and a wall 21 opposite the wall 15 and above the outer side of the explosion chamber 1^a. The inclined wall 22 lying above and limiting such explosion chamber 1^a is more sharply inclined than the wall 14, and at its right hand end (as viewed in Fig. 1) is continuous with the lower wall of an inclined passage 23 which extends transversely downward to a chamber 24 lying between the transverse partition 20 before mentioned and a wall 25 parallel thereto. A partition wall 26 between the walls 13 and 21 and oppositely inclined to the partition wall 22 extends from the vertical cross partition 20 to the vertical end wall 27 of the partition structure. An upwardly opening check valve 28 is arranged in the upper wall of the chamber 24 to a space 29 which opens at its rear, that is, through the wall 25, into the explosion chamber 1 of the motor. The turbine chamber 2^a communicates at its bottom with the irregular space between the walls 13 and 15 and above the inclined walls 22 and 26 which through the check valve 28 communicates with the explosion chamber 1. From the foregoing description it will readily be understood that a body of mercury driven from either ex-

plosion chamber through the turbine chamber with which it is in communication through the pipe 6 or 7, as the case may be, will pass through the check valve governing the outlet passage from said turbine chamber into the opposite explosion chamber, but that passage of fluid pressure in the opposite direction will be prevented.

The devices and means by which explosive vapor is introduced and discharged in the explosion chambers, and the spent products of combustion discharged, will next be described. For this purpose, where a reservoir of gas under pressure may conveniently be made use of, I have devised one form of distributing valve, illustrated more particularly in Figs. 5 to 8, while for situations where it may be desired to directly carburet and compress the charges of vapor as they are used I have devised a modified form of valve illustrated in Figs. 9 to 12.

Referring first to Figs. 5, 6, 7 and 8, the valve box or casing 30 for distributing the explosive vapor is secured to the front of the engine (on the righthand side, as viewed in Fig. 5), near the upper level of the explosion chambers, and within this valve box is arranged the reciprocating slide valve 31, having on its under face a channel 32 extending to the opposite ends of the valve. In one extreme position of the valve (to the left of the position as shown in Fig. 8), the port 35 is uncovered and in communication with the inlet port 33, while the port 34 is in communication, through a bridging channel 37 in the top wall of the valve, with an exhaust port 38, and in the other extreme position such supply and exhaust connections are reversed. In one intermediate position of the valve, partway between center position and extreme position in the direction first described, (illustrated in Fig. 8) the port 35 will be closed, but the port 34 will remain in communication with the exhaust port. In a second intermediate position (to the right, as viewed in Fig. 8) partway between the other extreme position and center position, the port 34 will be closed and the port 35 be at the same time connected with exhaust. From the ports 34 and 35, passages numbered on the drawings 34^a and 35^a, respectively extend rearwardly through the casing and communicate with the explosion chambers 1 and 1^a through the elongated ports 34^b and 35^b. Sparking plugs 39 and 40 adjacent such ports are seated in and close the rear ends of the passages 34^a and 35^a. Insulated conductors carried by these plugs terminate in electrodes 41 and 42 which are double convex in cross-section, the pointed ends of such electrodes extending nearly to the walls of the passages 34^a and 35^a, which walls are electrically connected to the other pole of the source of electric current and complete the circuit for the spark.

By means hereinafter described a spark is caused at the spark plug 40 as soon as the valve has shifted to the first intermediate position above mentioned, the valve remaining stationary for a time while an explosion takes place in the chamber 1^a, (which has previously been charged with gas) and while exhaustion of the contents of the chamber 1 takes place through the passage 34^a and exhaust passage, after which the valve shifts to extreme righthand position—as viewed in Fig. 8—when excess pressure in chamber 1^a will be instantly relieved through the passage 35 and exhaust port 10 while gas under pressure will be admitted through the port 34 and fill the passage 34^a and upper part of the chamber 1, and the valve then shifts back to the second intermediate position, in which such port 34 is 15 shut off from the supply of vapor under pressure and where it dwells while an explosion is caused in the chamber 1 by the spark plug 39, the chamber 1^a being meanwhile open to exhaust. The valve then moves 20 quickly to extreme lefthand position to relieve pressure in the chamber 1 and charge the chamber 1^a with gas, and in the continued operation of the engine this cycle of 25 operation is repeated.

The mechanism for shifting the valve 31 comprises a rod 43 having a pin and slot connection with the forward end of an intermediately pivoted lever 44 which at its rear end co-operatively engages a cam slot 30 formed in a cam disk 45 mounted upon a cross shaft 46 upon which is fixed a gear wheel 47 driven by a pinion 48 carried by the main shaft carrying the turbine wheels of the motor. The outline of the cam slot 35 and arrangement of the parts may be such that the valve will remain stationary at each of its intermediate positions about one-third of a revolution of the cam disk, and each traverse from one intermediate position and 40 back to the second intermediate position will occupy about one-sixth of a revolution of such disk, though considerable variations from this turning of the valve movements may be necessary in engines of varying 45 proportions and designed to run at different speeds.

While it will be understood that any suitable sparking system connected so as to be operated by a moving part of the engine 50 may be used to cause sparks at the spark plugs 39 and 40 at the proper instants, I have illustrated in Figs. 13 and 14 a rotary switch suitable for the purpose. This switch consists of a fiber casing 49 secured 55 to the casing of the engine, surrounding the cross-shaft 46 and equipped with binding posts 50 and 51 for electrically connecting conductors connected with the spark plugs with diametrically opposite spring contact 60 members 52 and 53. These members are arranged to co-operate with a rotating contact member consisting of a metal roller 54 mounted between a pair of metal rings 55 and 56 secured to the opposite faces of a fiber disk 57 at the edges thereof, which disk 70 is mounted to rotate with the shaft 46 within the casing. The ring 56 co-operates with a metal spring pressed roller 58 carried by the casing and electrically connected by conductor 59 with one pole of the source of 75 electric current, the other pole being connected to the frame or casing of the engine, which thus serves as a ground. It is evident that at each revolution of the shaft 46 the circuit will be made and broken once at 80 each contact, and the arrangement is such that this causes a spark at the proper moment in the associated explosion chamber, each of which is charged with gas once at 85 each revolution of the cam disk 45 mounted upon the same shaft.

In Figs. 10 and 11 I have illustrated a slightly modified form of valve which is associated with a piston arranged to compress and supply charges of gas through the valve 90 in synchronism with its movements. In this arrangement, the ports 60, 61 (corresponding to the ports 34 and 35, respectively) are uncovered by the valve 67 at the limit of its stroke in opposite directions. 95 Opposite the ports 60 and 61 and in the lower wall of the valve box are ports 63 and 62 opening into opposite ends of the piston chamber, and relief passages or channels formed in the lower face of the valve afford 100 constant communication between the ends of the valve chamber and adjacent ends of the piston chamber. As the valve uncovers the port 61 it permits free and direct communication from the adjacent end of the 105 piston chamber through the port 62 and said port 61 into the explosion chamber 1^a, and at the other end of its traverse it simultaneously uncovers the ports 60 and 63 and permits passage of gas from the opposite 110 end of the chamber into the chamber 1. The lower opposite ends of the piston chamber are provided with check valves 64 and 65 communicating in common with a supply pipe through which explosive vapor is 115 drawn. This supply pipe may be connected to any suitable carburetor for furnishing a supply of carbureted vapor, or a reservoir of gas and regulating apparatus for supplying with the gas a proper proportion of air 120 to form an explosive mixture. The piston 66 is reciprocated by means to be hereinafter described, and the arrangement and adjustment of parts is such that a charge of vapor drawn through the valve 64 into one 125 end of the cylinder at a stroke of the piston in one direction will be compressed to its maximum pressure by a stroke in the opposite direction just as the valve 67 uncovers the ports 61 and 62; and in like manner the 130

piston will reach the limit of its return stroke simultaneously with the uncovering of the ports 60 and 63.

For the purpose of reciprocating the piston I have in the present instance provided the piston rod 68 with a double right and left screw-thread 69 which co-operates with an internal thread within the hub of a sprocket wheel 70 mounted to rotate in a fixed bearing on the casing or frame of the motor. The piston rod has a splined engagement with the motor frame, preventing any rotary movement from being communicated to it by the sprocket wheel, and at opposite ends of the screw threads is provided with springs 71 and 72, bearing against collars secured to it. The sprocket wheel 70 is rotated by a sprocket chain 73 traveling around a second sprocket wheel 74 carried by the main shaft of the motor, and acting in a well-known manner upon the threads on the piston rod causes it to reciprocate. The gearing and adjustment of the valve 67 and piston 66 are such that they will be operated in synchronism in the manner before described.

In order to save any mercury that may be volatilized in the continued operation of the engine the products of combustion are conducted from the exhaust port 38 through the pipe 75 through a condensing apparatus consisting of a tank of water 76 provided with baffle plates 77, the pipe 75 opening into said tank at its bottom, so that the spent products will follow a tortuous course through the water and the mercuric vapor be condensed and settle to the bottom, where it may be drawn off from time to time.

In the modified form of engine shown in Figs. 15 and 16, the explosion chambers 78 and 79, communicating with the turbine chambers 80 and 81 above them through passages such as shown in the engine previously described, and operating by the impact of a body of mercury alternately acting on the turbine wheels 82 and 83, constitute one engine; while the explosion chambers 84 and 85, turbine chambers 86 and 87, and a second body of mercury acting on the turbine wheels 88 and 89 constitute a second engine having the same motor shaft 90 and operating through connections as those hereinbefore described to reciprocate a common, double valve 91 to admit vapor to the explosion chambers and exhaust the products of combustion therefrom. The valve arrangement is a modification of that before described, and is such that when the valve is in the position shown in Fig. 16, gas is admitted simultaneously to the outside chambers 78 and 85 through a chamber 92 around a reduced connecting-stem portion of the valve and a channel 93, ports 94 and 95, and passages 96 and 97 communicating respectively

with said chambers; while the products of combustion are exhausted from the inside chambers 79 and 84 through ports opening into a common passage 98 terminating at a port 99 in the valve casing which at the time is in communication through a bridging channel 100 with the exhaust passage 101. From this position of the valve, which is its extreme left hand position, the valve shifts to the right a sufficient distance to cover the ports 94 and 95 when by suitable means, such as those before described, an explosion is caused in the chambers 78 and 85, the chambers 79 and 84 being still open to the exhaust passages. The valve then shifts to extreme right hand position, in which the port 99 communicating with chambers 79 and 84 is in communication with the sources of vapor supply, while the channel 100 connects the port 95 and chamber 85 with the exhaust passage 100, and a second channel 102 places the port 94 and chamber 78 also in communication with the exhaust. The valve next shifts to the left a short distance to cover the port 99, when an explosion is caused in the chambers 79 and 84, the chambers 78 and 85 still remaining open to exhaust.

I claim:

1. A motor of the character described and including casing members formed with a pair of separate turbine chambers, a turbine wheel in each chamber, both wheels being connected to a common motor shaft, a pair of explosion chambers respectively communicating with inlets to said turbine chambers, a pair of separate cross passages leading respectively from the outlet of the two turbine chambers to the opposite explosion chambers, a body of liquid arranged to circulate through said chambers and passages successively in one direction, and means for exploding charges of fuel alternately in said explosion chambers. 95

2. A motor of the character described and including casing members formed with separate turbine chambers arranged in pairs, turbine wheels in said chambers operatively connected to a common motor shaft, pairs of explosion chambers corresponding to said turbine chambers respectively communicating with the inlets to said turbine chambers, pairs of separate cross passages leading respectively from the outlet of each turbine chamber to the opposite explosion chamber of its pair, a body of liquid in each pair of chambers and passages arranged to circulate successively in one direction therethrough, and means for exploding charges of fuel alternately in the members of each pair of explosion chambers. 100 115

3. A motor of the character described and including casing members formed with a pair of turbine chambers, a turbine wheel in

each chamber, both wheels being connected to a common motor shaft, a pair of explosion chambers respectively communicating with inlets to said turbine chambers, a valve-governed cross passage leading from the outlet of each turbine chamber to the opposite explosion chamber, a body of liquid arranged to circulate through said chambers and passages, and means for exploding charges of fuel alternately in said explosion chambers.

4. A motor of the character described and including casing members formed with a pair of turbine chambers, a turbine wheel in each chamber, both wheels being connected to a common motor shaft, a pair of explosion chambers, passages respectively leading from the bottoms of said chambers to the inlets to said turbine chambers, a valve-governed cross passage leading from the outlet of each turbine chamber to the opposite explosion chamber, a body of liquid arranged to circulate through said chambers and passages, and means for exploding charges of fuel alternately in said explosion chambers.

5. A motor of the character described and including casing members formed with a pair of parallel vertically-disposed turbine chambers, a turbine wheel in each chamber, both wheels being mounted on a common motor shaft, a pair of parallel vertically-disposed explosion chambers arranged below said turbine chambers, an upwardly extending tubular conduit arranged in each explosion chamber with its open lower end adjacent the bottom of said chamber and forming a passage communicating with the inlet to the turbine chamber thereabove, a valve-governed cross passage between the outlet of each turbine chamber and the opposite explosion chamber, a body of liquid arranged to circulate through said chambers and passages, and means for exploding charges of fuel alternately in said explosion chambers.

6. In a motor of the character described and having an upper casing member formed with turbine chambers and a lower casing member formed with explosion chambers, a partition plate separating the chambers in said upper and lower members, and provided with valve-governed cross passages connecting the outlet of each turbine chamber and the top of the opposite explosion chamber.

7. In a motor of the character described and having an upper casing member formed with turbine chambers and a lower casing member formed with explosion chambers, a partition plate separating the chambers in said upper and lower members, and including a central vertical wall, inclined bottom walls on opposite sides of said central wall, the lowest portions of said bottom walls being each formed with an opening and a connecting transverse passage communicating

with the top of the opposite explosion chamber, and a check valve arranged in each transverse passage.

8. In a motor of the character described and having an upper casing member formed with a pair of turbine chambers, a lower casing member formed with a pair of parallel explosion chambers and a pair of supply and exhaust passages extending through the casing parallel with said explosion chambers and in open communication therewith, corresponding ends of the two passages being equipped with spark plugs, and valve means at the other ends of such passages for reversing the supply and exhaust connections.

9. In a motor of the character described and having an upper casing member formed with a pair of turbine chambers, a turbine wheel in each chamber, both wheels being connected to a common motor shaft, a lower casing member formed with a pair of parallel explosion chambers and a pair of supply and exhaust passages extending through the casing parallel with said explosion chambers and in open communication therewith, corresponding ends of the two passages being equipped with spark plugs, valve means at the other ends of such passages operatively connected with the motor shaft for reversing the supply and exhaust connections, and timing means operated by said shaft for causing sparks at said plugs.

10. A motor of the character described and comprising casing members formed with a pair of turbine chambers and a corresponding pair of explosion chambers, and passages connecting corresponding turbine and explosion chambers, and cross passages connecting opposite turbine and explosion chambers, said explosion chambers having supply and exhaust connections, turbine wheels in said turbine chambers, both wheels being connected to a common motor shaft, a supply of explosive vapor, a valve operatively connected with the motor shaft for reversing said supply and exhaust connections to alternately supply vapor to said explosive chambers and exhaust spent products of combustion therefrom, and a timing means operated by said shaft for causing sparks at said plugs.

11. A motor of the character described and comprising casing members formed with a pair of turbine chambers and a corresponding pair of explosion chambers, and passages connecting corresponding turbine and explosion chambers, and cross-passages connecting opposite turbine and explosion chambers, said explosion chambers having supply and exhaust passages; turbine wheels in said turbine chambers, both wheels being connected to a common motor shaft, a piston operatively connected with said motor shaft for compressing charges of explosive vapor,

and a valve also connected with said motor shaft for governing the admission of such charges of vapor to the explosion chambers and the exhaust of spent products of combustion therefrom.

12. A motor of the character described and comprising casing members formed with a pair of turbine chambers and a corresponding pair of explosion chambers, and passages connecting corresponding turbine and explosion chambers, and cross-passages connecting opposite turbine and explosion chambers, said explosion chambers having supply and exhaust passages; turbine wheels 10 in said turbine chambers, both wheels being connected to a common motor shaft, a cam rotated by said motor shaft, a rocking lever operated by said cam, and a reciprocating valve operated by said rocking lever and 15 arranged to govern the admission of explosive vapor to the explosion chambers, and the exhaust of spent products of combustion therefrom.

13. A motor of the character described

and comprising casing members formed with 25 a pair of turbine chambers and a corresponding pair of explosion chambers, and passages connecting corresponding turbine and explosion chambers and cross-passages connecting opposite turbine and explosion chambers, said 30 explosion chambers having supply and exhaust passages; turbine wheels in said turbine chambers, both wheels being connected to a common motor shaft, a piston for compressing charges of explosive vapor, a double-threaded screw carried by the stem of said piston for reciprocating the same, a rotating nut coöperating with said screw, a sprocket connection intermediate the motor shaft and 35 said nut, and a valve connected with said motor shaft for governing the admission of said charges of vapor to the explosion chambers and the exhaust of spent products of combustion therefrom.

HAROLD H. TURNER.
